United States Patent Office

Des. 180,693
Patented July 23, 1957

180,693

TOOTH PICK DISPENSER

Elmer E. Mosley, Fort Worth, Tex.

Application January 5, 1956, Serial No. 39,607

Term of patent 14 years

(Cl. D52—2)

FIGURE 1

The undisclosed side of the toothpick dispenser is substantially plain in appearance.

I claim:

The ornamental design for a tooth pick dispenser, substantially as shown and described.
